(57) **CLAIM**

The ornamental design for an inflator, as shown and described.

DESCRIPTION

FIG. 1 is a perspective view of the inflator;

FIG. 2 is a front view of the inflator depicted in FIG. 1;

FIG. 3 is a rear view of the inflator depicted in FIG. 1;

FIG. 4 is a top view of the inflator depicted in FIG. 1;

FIG. 5 is a bottom view of the inflator depicted in FIG. 1;

FIG. 6 is a left side view of the inflator depicted in FIG. 1; and,

FIG. 7 is a right side view of the inflator depicted in FIG. 1.

The broken lines illustrate ancillary tubing and components that form no part of the claimed design.
